CLAIM

The ornamental design for an electrical plug, as shown and described.

DESCRIPTION

FIG. 1 is a perspective view of the preferred embodiment of an electrical plug showing my new design;

FIG. 2 is a front view of the preferred embodiment of an electrical plug showing my new design;

FIG. 3 is a back elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in the drawings are included for the purpose of illustrating unclaimed portions of the electrical plug and form no part of the claimed design.
